INSULATOR

Arthur O. Austin, near Barberton, Ohio, assignor,
by mesne assignments, to The Ohio Brass Com-
pany, Mansfield, Ohio, a corporation of New
Jersey

Application March 1, 1929, Serial No. 343,597

6 Claims. (Cl. 173—313)

This invention relates to insulators of a bus or switch type and has for one of its objects the provision of an insulator to which the connected parts may be readily and economically attached and in which the attaching means will be strong and effective, and at the same time, sufficiently resilient to prevent injury to the dielectric member.

A further object is to provide an insulator of the class named which shall be of improved construction and operation.

Other objects and advantages will appear from the following description.

The invention is exemplified in the combination and arrangement of parts shown in the accompanying drawing and described in the following specification, and it is more particularly pointed out in the appended claims.

In the drawing:

Fig. 1 is an elevation partly in section showing one embodiment of the present invention.

Fig. 2 is a top plan view of the insulator cap taken on line 2—2 of Fig. 1.

Fig. 3 is a fragmentary elevation of a modification.

Fig. 4 is a fragmentary section on line 4—4 of Fig. 2.

High voltage transmission installations require switches or other pieces of apparatus for connecting and disconnecting the line. The live parts of these switches have to be insulated from ground or the supporting structure. In insulating the various parts, rigidity, mechanical strength, reliability, and cost are all important factors. The present invention provides a new and improved type of insulator suitable for mounting switch or bus parts or for other purposes required in power stations.

In the form of the invention shown in the drawing, the insulating member 10 is provided with a metal cap 11 cemented to the insulating member by cement 12. The insulator is also provided with a rigid post 13 having a roughened section 14. Transfer of stress between this member and the dielectric member 10 is provided by the cement joint 15. The post 13 is provided with an enlarged portion or flange 16 which is equipped with grooves 17 and a tapped hole 18. The cap 11 is provided with a centrally disposed boss 29, riveted or otherwise fixed thereto and provided with a central tapped hole 19 corresponding to the hole 18 in the base 16. The cap 11 as shown in Fig. 2, is provided with radial grooves 20 similar to the grooves 17.

The cap is the resilient type of construction

shown in my prior Patent No. 1,284,976. Resiliency is obtained by waving the cap or by the slots 21. The cap is provided with grooves 22 which may be pressed or cut into the metal or provided in any suitable manner. The cap and 60 the base are provided with grooves 17 and 20 or with depressions 23 and 24. These depressions are for the purpose of receiving projections 25 or 26 on the parts attached to the insulator as shown in Fig. 3 to maintain alignment and resist 65 torsional stress. Other methods may be used to insure alignment such as a pin 27 arranged to be inserted in the grooves 17 and 20 and extending into registering grooves in the attached members. The pins 27 may be provided with a lock- 70 ing groove 28 to hold them in place.

The member 26 may be a loose fitting rivet and, having its stem extending into an opening in one of the connected parts, it will be held in place. The cap construction consists in general of a 75 pressed metal housing into which the boss 29 is secured. This boss may be riveted, crimped or welded in position.

Owing to the fact that grooves rather than projections are provided for in both the base of 80 the pin and the cap, it is possible to mount either end of the insulator on flat surfaces so that switch parts or bus parts may be mounted on either the top of the insulator or the bottom of the insulator as desired. The type of construction is particularly applicable to multipart 85 insulators, although the general application is the same whether a single insulator unit is used or a plurality of units are assembled one on top of the other. The light-strong, metal construction of the locking grooves makes it possible to obtain relief for thermal stress due to differential 90 expansion or contraction between the metal and dielectric and, at the same time, permits of a reliable mechanical combination. In forming 95 the resilient type cap, V-shaped sections may be cut from the blank at spaced points about its periphery which greatly facilitates the forming of the cap and provide the slits 21 after the cap is pressed into shape. When the cap is pressed 100 in the final form, the V shaped slots are closed, making a good reliable construction.

In the embodiment illustrated, switch clips 30 are fastened to a base member 31 secured to the cap 11. The base member is fastened to the 105 insulator by means of a stud bolt 32 and nut 33 or by a cap screw where space will permit. It is evident that where a bolt may be passed through a mounting member, a cap screw is all that is necessary for mounting. Where the locking 110

grooves 20 are provided, it is a very easy matter to provide the necessary locking elements in the base member 31. These elements may be small raised projections on the lower face of the base member, or holes may be drilled in the base member and round head rivets inserted, so that the rivet heads form the projections. With the radial groove, all that is necessary is to place the round headed locking rivet loosely in its drilled hole as close spacing is not necessary. In many installations, friction may be depended upon to hold the parts in place. Where the locking grooves 20 are used, the resulting ribs on the lower face of the cap may be fitted into grooves 15 on the upper face of the dielectric member 10, as shown in Fig. 4 tending to line this member up. The improved construction provides an insulator of the highest degree of mechanical reliability and a low cost of production and when 20 provided with locking means has the same advantages as prior insulators using several bolts to prevent rotation.

I claim:

1. In combination a dielectric member, a sheet 25 metal cap secured to said dielectric member and having a central opening therein, an insert fixed in said opening and projecting into said cap, said insert being substantially flush with the outside surface of said cap and having a tapped 30 hole therein, a conducting member mounted on said cap, and a screw threaded into said opening for holding said conducting member to said cap.
2. In combination an insulator having a depression in the face thereof, a cap secured to 35 said insulator and having an opening therein, an insert disposed within said opening and permanently and rigidly secured to said cap and extending into the depression in said dielectric member, said insert having an internally threaded 40 socket therein, a conducting member mounted on said cap and a screw threaded into said socket for securing said conducting member to said cap.
3. In combination an insulator cap formed of 45 sheet metal and having a central opening therein and radial depressions formed in the surface

thereof, and an insert secured to said cap within said opening for attaching a conducting member to said cap.

4. In combination an insulator cap comprising a cup shaped member formed of sheet metal and having slots in the rim thereof to provide resiliency, said cap having a central opening therein, and an insert secured to said cap within said opening and projecting into the interior of said cap, said insert having an outwardly opening recess therein, the recess being threaded to receive a screw, and the upper surface of said cap having radial grooves therein for receiving aligning members. 80 85

5. In combination an insulator cap comprising a cup shaped member formed of sheet metal and having slots in the rim thereof to provide resiliency, said cap having a central opening therein, and an insert secured to said cap within said opening and projecting into the interior of said cap, said insert having an outwardly opening recess therein, the recess being threaded to receive a screw, and the upper surface of said cap having radial grooves therein and cup shaped 90 95 depressions for receiving aligning members. 100

6. An insulator comprising a dielectric member having a cup shaped depression in one face thereof and having grooves radiating from said depression, a sheet metal cap having a central opening therein, an insert secured to said cap 105 within said opening and extending into the depression in said dielectric member, said cap having radial grooves in the outer surface thereof and registering radial ribs on the inner surface thereof, said ribs being disposed in the grooves 110 in said dielectric member, said insert having a threaded recess therein, a conductor mounted on said cap, a screw threaded in said recess for holding said conductor to said cap, and locking members engaging the grooves on the face of 115 said cap and held by said conductor for preventing rotation of said conductor relative to said cap. 120
